M. M. McNamara.

Inventor
Wm R Cole

UNITED STATES PATENT OFFICE.

WILLIAM R. COLE, OF DETROIT, MICHIGAN, ASSIGNOR TO HIMSELF, FRANK G. SMITH, AND GEORGE W. MOORE, TRUSTEES, ALL OF SAME PLACE.

TELEPHONE-TRANSMITTER.

SPECIFICATION forming part of Letters Patent No. 351,250, dated October 19, 1886.

Application filed March 3, 1885. Serial No. 157,689. (No model.)

To all whom it may concern:

Be it known that I, WILLIAM R. COLE, of Detroit, county of Wayne, and State of Michigan, have invented a new and useful Improvement 5 in Microphone-Transmitters; and I do declare that the following is a full, clear, and exact description thereof, reference being had to the accompanying drawings, which form a part of this specification.

10 The nature of this invention relates to certain new and useful improvements in telephone-transmitters, the object of which is to give a strong undulatory current without any break in the connection, so that the articulation may 15 be clear and distinct, and to obviate the frying and metallic sounds produced in transmitters where the connection is not absolutely maintained.

Figure 1 is a longitudinal section on line $x x$ 20 of Fig. 2, showing the various parts. Fig. 2 is a perspective view of the same.

In the accompanying drawings, which form a part of this specification, A represents a metal diaphragm; B, a rubber ring upon which 25 the diaphragm rests.

C is a wooden base on which the rubber ring is held.

D is a mouth-piece.

e e are clamps for holding the diaphragm 30 in its place.

F is a polarized magnet hung on trunnions g , which trunnions are pivoted between lugs of yoke h , which bridges over the diaphragm and is securely fastened to the base C, leaving 35 a space, so that it does not interfere with the vibrations of the diaphragm.

I is a platinum point secured to the center of the diaphragm.

J is a carbon button.

40 K is a brass or other unmagnetizable metal screw that forms a socket for holding the

carbon button, and is also used for adjusting the same.

L is an adjusting screw of unmagnetizable metal, to prevent the magnet from tipping forward and engaging the diaphragm. 45

In operation the carbon button is adjusted to allow the magnet to attract toward the center of the diaphragm until the required amount of pressure is brought to bear upon the platinum point. The small screw L is then adjusted so as not to interfere with the vibrations, but so as to prevent the magnet from changing its position under heavy vibrations. The carbon button never leaves the platinum 55 point, thus preventing oxidization, and the articulations are clear and distinct. The vibrations of the diaphragm upon the carbon button increase or decrease the attraction of the magnet at either end, thus varying the undulatory currents as required. 60

What I claim as my invention is—

1. In a telephone-transmitter, the combination, with the diaphragm, a yoke bridging the same, trunnions pivotally supported by said 65 yoke, and a permanent magnet supported by said trunnions, of a carbon, and screws for adjusting the pressure of the carbon upon the diaphragm, substantially as described.

2. In a telephone transmitter, the combination, with the ring C, rubber ring B, diaphragm A on said ring B, and clamps holding said ring and diaphragm to the ring C, of the yoke bridging said diaphragm and provided with lugs h , trunnions g , journaled in said lugs, magnet F, 75 supported by said trunnions, carbon J, and adjusting-screws K L, all substantially as and for the purposes specified.

WILLIAM R. COLE.
